(57) **CLAIM**

The ornamental design for a wood dust collector, as shown and described.

DESCRIPTION

FIG. 1 is a front perspective view of a wood dust collector showing my new design;

FIG. 2 is a rear perspective view thereof;

FIG. 3 is a front elevational view thereof;

FIG. 4 is a rear elevational view thereof;

FIG. 5 is a left side view thereof; and,

FIG. 6 is a right side view thereof.

The broken lines in the figures are for the purposes of illustrating portions of the wood dust collector, which form no part of the claimed design.
